UNITED STATES PATENT OFFICE.

JOHN C. HERTLE, OF BROOKLYN, N. Y., ASSIGNOR TO VAN GELDER & CO.

FLANGING-MACHINE FOR SWEAT-BANDS.

SPECIFICATION forming part of Letters Patent No. 231,668, dated August 31, 1880.

Application filed July 1, 1880. (No model.)

To all whom it may concern:

Be it known that I, JOHN C. HERTLE, of the city of Brooklyn, county of Kings, and State of New York, have invented an Improvement 5 in Flanging-Machines for Sweat-Bands, of which the following is a specification.

My invention relates to flanging-machines designed to flange sweat-bands for hat-bodies; and it consists in mechanism operated in connection with the guide-foot and flanging-head whereby a uniform pressure may be brought to bear upon the guide and flanging-head to guide and flange sweat-bands of various thicknesses with the same pressure automatically, 15 and which mechanism is fully set forth in the following specification, shown in the accompanying drawings, and referred to in the appended claims.

The object of my invention is to so construct 20 a flanging-machine for flanging sweat-bands that the pressure exerted by the flanging-head to flange the said band and the guide is the same for all sweat-bands, even though they vary greatly in thickness, and so produce uniform results.

In the drawings, Figure 1 is a perspective view of a flanging-machine embodying in it 25 my improvements. Fig. 2 is a section of a portion of same, showing the flanging-head and feeding-roller. Figs. 3 and 4 show sections of the slides which are situated on the pressure-bars, and the movement of which governs the pressure of the flanging-head and guide.

A is the frame of the machine. B is a shaft, having bearings in said frame A, and carrying on one end the feed-roller and former D, and on the other a pinion, E.

Situated over the shaft B is a frame, C', 40 which is pivoted at c and carries a shaft, C. This frame C' is kept from lateral movement and yet allowed movement on one end by moving in slots a a in frame A.

The shaft C has rigidly secured to it two 45 collars, H and H', and upon one end the flanging-head G, and upon the other the pinion E, which meshes with pinion F on shaft B, situated below. The shaft C is free to slide longitudinally in its bearings in frame C'.

Meshing with pinion E is a pinion, U, which

is secured upon one end of the driving-shaft U', carrying on the other end the driving-wheel U², and working in bearings at u u.

Passing through the frame A, at the top, and resting upon the frame C', is a pin, C², 55 and resting upon this pin C² is a lever, C³, having its fulcrum at A', and carrying a weight, C⁴, with which the pressure of the flanging-head G upon the feeding and former roll D is regulated and made uniform.

Attached to the frame A is a bar, I, and pivoted to this bar is the pressure-lever J, whose fulcrum is at j. This lever J carries an idler-roller, J', which rests against the collar H on shaft C. Upon the outer end of this 65 lever J is a slide, K, to which a cord, k, is attached and then passes over the idler-pulley L, held upon shaft l, and free to slide laterally thereon, said shaft being supported in a frame, T. The end of the cord k, after passing over 70 the pulley L, is attached to a weight, L'. By this means any pressure desired can be put upon the lever J, and, through the agency of the roller J', upon the shaft C and flanging-head G, to cause its flange g to press upon the 75 flange d of the former-roller D. It is evident that this pressure must be uniform, however great the lateral movement given to the head G. If it is desired to lessen this pressure the slide-plate K is moved along the lever J toward its fulcrum j, the idler-pulley following it along its shaft l.

The slide K is provided with a knob, k', with which to move it, and on one side with a ring-piece, k², to which the cord is attached, and 85 on the bottom with a spring, t, kept in place by a bar, t'. The spring t presses tightly upon the lever J, and so holds the slide K wherever it is placed. Situated below this lever J is another and similar lever, Q, whose fulcrum 90 is at q', and which has in place of the roller J' a pin, q.

The slide R corresponds to slide K, and idler-pulley S to pulley L. The pin q, attached to lever Q, presses against a collar, P', screwed 95 upon a shaft, O, having bearings in the frame A, and in which it reciprocates longitudinally. Upon one end of this shaft O is the guide-foot V, which moves over a guideway, W, and presses the sweat-band between the side of 100

the foot and the upright wall w . Upon the other end of rod or shaft O is a nut or collar, P , carrying a pin, p .

Situated under lever Q is another lever, N' , 5 whose fulcrum is at n' , and which is attached or pivoted to the rod N at n . This rod N works through a hole in the frame A , and is pivoted at its outer end to a lever, M , whose fulcrum is at c' , and which is provided with a 10 pin, m , which rests against the pin p of the collar P on the shaft O . The upper part of the lever M , near its fulcrum, rests against the collar H' on the shaft C , to which the flanging-head G is secured. Lever N is the operating- 15 lever.

The operation is as follows: The lever N is pressed to the left, thereby forcing out the guide-foot V and raising the weight S' by oscillating the lever Q , and forces out the flanging-head G to the position shown in dotted lines, raising the weight L' by oscillating the lever J . These movements to the foot V and head G are caused by the movement of the rod N 20 and lever M , which latter acts upon the shafts directly. The machine being in motion, the sweat-band, after being sewed, is bent over and the edge placed between the foot V and the upright wall w and fed up to the flanging-head G . The lever N' is now relieved, and the weights 25 S' and L' come into play, and, acting through the levers Q J , collars P' H , and shafts O C , the head G and foot V are pressed back upon the sweat-band, which is now fed between the head G and former-roller D , and is flanged or 30 has the edge creased and bent over. Should the sweat-band be very thick, and there should not be sufficient room vertically between the flanging-head G and roller D , then the former will be raised, lifting the weighted lever C^3 . 35 By the adaptions of levers and weights to the flanging-head G and guide-foot V the same pressure is exerted automatically to flange all sweat-bands, whether thick or thin. The shafts B and C are rotated in opposite directions at about the same speed; but the flanging-head G being very much greater in diameter 40 than the former-roller, D , its periphery moves with a higher velocity; and since the sweat-band is fed through the machine with a speed governed by the former-roller D , the said sweat-band will be creased or flanged by the flanging-head pressing upon it and sliding over it 45 at the same time. The collar P is adjustable on rod or shaft O , so as to regulate the movement of the foot V against the wall or guide w . 50 55

I claim—

1. In a flanging-machine for flanging sweat-bands, mechanism which gives a uniform pressure automatically, both laterally and vertically, to the flanging-head for any thickness 60 of sweat-band, substantially in the manner set forth.

2. In a flanging-machine for flanging sweat-bands, mechanism which puts the flanging-head automatically under a uniform pressure 65 in a direction to the plane of said head, in combination with mechanism which puts the guide-foot under uniform pressure, automatically, in a direction parallel to that of the flanging-head, for the purpose of flanging varying 70 thicknesses of sweat-bands with the same pressure, substantially as set forth.

3. In a machine for flanging sweat-bands, mechanism which operates the guide-foot in such a manner that a uniform pressure is put 75 upon sweat-bands varying in thickness, automatically, thereby making the drag to the feed always uniform.

4. In a flanging-machine for flanging sweat-bands, the combination of shaft C , carried in 80 a frame, C' , flanging-head G , former-roller D , pin C^2 , lever C^3 , weight C^4 , collar H , lever J , slide K , cord k , idler-pulley L , shaft l , and weight L' , substantially as and for the purpose specified. 85

5. In a machine for flanging sweat-bands, the pressure-lever J , for imparting a lateral pressure to the flanging-head, in combination with an adjustable slide, K , cord k , passing over idler-pulley L to slide upon shaft l and 90 adjust itself to the position of the slide, and weight L' , substantially as and for the purposes described.

6. In a machine for flanging sweat-bands, mechanism which gives uniform pressure vertically and automatically to the flanging-head for sweat-bands of varying thicknesses, substantially in the manner set forth. 95

7. In a machine for flanging sweat-bands, the combination of shaft O , adjustable collar 100 P , guide-foot V , passing through wall w , lever Q , pin q , slide R , cord k , idler-pulley S , shaft s , and weight S' , substantially as and for the purposes set forth.

In testimony of which invention I hereunto 105 set my hand.

JOHN C. HERTLE.
